(57) **CLAIM**

The ornamental design for a set of building blocks as shown and described.

DESCRIPTION

FIG. 1 is a front, right and top perspective view of a set of building blocks, showing my new design.

FIG. 2 is a rear, left and bottom perspective view of a set of building blocks, showing my new design.

FIG. 3 is a front, right and top perspective view of a Component 1 of the set of building blocks in FIG. 1.

FIG. 4 is a rear, left and bottom perspective view thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof.

FIG. 10 is a bottom plan view thereof.

FIG. 11 is a front, right and top perspective view of the Component 2 of the set of building blocks in FIG. 11.

FIG. 12 is a rear, left and bottom perspective view thereof.

FIG. 13 is a front elevation view thereof.

FIG. 14 is a rear elevation view thereof.

FIG. 15 is a left side elevation view thereof.

FIG. 16 is a right side elevation view thereof.

FIG. 17 is a top plan view thereof; and,

FIG. 18 is a bottom plan view thereof.

1 Claim, 18 Drawing Sheets
